UNITED STATES PATENT OFFICE.

GEORGE T. PERKINS AND MILTON HILL, OF CLEVELAND, MINNESOTA.

RAILWAY-JOINT.

SPECIFICATION forming part of Letters Patent No. 681,075, dated August 20, 1901.

Application filed April 27, 1901. Serial No. 57,788. (No model.)

To all whom it may concern:

Be it known that we, GEORGE T. PERKINS and MILTON HILL, citizens of the United States, residing at Cleveland, in the county of Lesueur and State of Minnesota, have invented certain new and useful Improvements in Railway-Joints; and we do hereby declare the following to be a full, clear, and exact description of the invention, such as will enable others skilled in the art to which it appertains to make and use the same.

This invention has relation to railway rail joints or fasteners, and has for its object the provision of a rail joint or fastener of novel construction intended and adapted to secure railway-rails in proper alinement, prevent breakage, permit of longitudinal movement or play of the rails under changes in temperature, and lock or secure the rails against longitudinal displacement when subjected to the thrust or pull of heavy loads and on steep grades.

The invention consists in the novel construction and combination of parts, as hereinafter described and claimed.

In the accompanying drawings, illustrating the invention, Figure 1 is a side elevation of our improved rail joint or fastener applied to the ends of two alined rails. Fig. 2 is a horizontal section on the line X X of Fig. 1. Fig. 3 is a vertical transverse section on the line Y Y of Fig. 1.

Referring to the drawings, A A designate the rails, and B the fish-plates, which latter are formed integral with the blocks or abutments C C and designed to fit against the web of the rail, between the head and bottom flanges. The fish-plates B B are formed with bolt-holes D D to secure them to the rails, and the latter are formed with longitudinal slots d d for the passage of said bolts, the slots being of sufficient length to allow the rails to contract and expand under the changes of temperature without strain on the joint structure.

The abutments C C are formed with square bases E, which rest in recesses in the ties F and are secured thereto by spikes e e, the ends of the recesses being close to the ends 50 of the abutments C C, so that when the parts are in position spreading of the rails at the

joints is prevented. The abutments are notched or recessed at G, so as to embrace the rails at their bases b b and extend under the rails until their inner ends meet or approximately meet.

Vertical holes c c are bored through the abutments C C, and through these holes spikes are driven into the tie, the spikes passing through the notches or recesses G and through slightly-elongated notches h h, formed in the bases of the rails, thus securely fastening the fish-plates and their abutments to the tie, while allowing the rails to slightly yield lengthwise under strain or changes of temperature.

By the structures herein described the rail-fastening or joint-securing devices are firmly attached to the tie, so that they cannot be moved either lengthwise of the rails or laterally. The rails are firmly secured against spreading or any displacement or shifting other than is necessary for safety and expediency.

The abutments C C are comparatively massive, forming strengthening reinforcements to the fish-plates and bracing the rails at points near the joint. As illustrated, the abutments begin at the upper edges of the fish-plates, where for a short distance they 80 form a thickening of the latter, as at k. The upper surfaces proper of the abutments are leveled, and from such surfaces the sides of the abutment flare outwardly to their bases E, which extend some distance farther to form 85 flanges for the reception of the heads of the spikes. The two abutments when in position with the fish-plates in contact with the webs of the rails form a compact, steady, and secure rail-chair.

Having described our invention, what we claim, and desire to secure by Letters Patent, is—

1. In railway-rail joints, the combination with the rails having elongated bolt holes or slots through their web portions and elongated notches in their bases, of the combined fish-plates and rail-supports, comprising the plates B, B, and the abutments C, C, the latter being formed with notches or recesses G G to receive the bases of the rails, and with spike-holes c, c, substantially as described.

2. In railway-rail joints, the combination with the rails having elongated bolt-holes in their webs, and elongated notches in their bases, of the recessed tie, and the combined rail chair and joint or joint connection, comprising the fish-plates B, B, and the abutments C, C, formed integral therewith, said abutments being formed with vertical holes through which spikes pass into the tie and

through the rail-notches substantially as described.

In testimony whereof we affix our signatures in presence of two witnesses.

GEORGE T. PERKINS.
MILTON HILL.
